US00D535259S

(12) **United States Design Patent** (10) **Patent No.:** **US D535,259 S**
Rodrigues et al. (45) **Date of Patent:** ** *Jan. 16, 2007

(54) **COAXIAL CABLE CONNECTOR**

(75) Inventors: **Julio F. Rodrigues**, Collierville, TN (US); **Salvatore J. Abbruzzese**, Piscataway, NJ (US); **Brian S. Welborn**, The Woodlands, TX (US)

(73) Assignee: **Thomas & Betts International, Inc.**, Sparks, NV (US)

(*) Notice: This patent is subject to a terminal disclaimer.

(**) Term: **14 Years**

(21) Appl. No.: **29/228,454**

(22) Filed: **Apr. 22, 2005**

Related U.S. Application Data

(60) Continuation of application No. 29/176,413, filed on Feb. 21, 2003, now Pat. No. Des. 505,391, which is a division of application No. 09/852,343, filed on May 9, 2001, now Pat. No. 6,530,807.

(51) **LOC (8) Cl.** **13-03**

(52) **U.S. Cl.** **D13/151; D13/133**

(58) **Field of Classification Search** D13/133, D13/151; 439/578, 584, 585, 583

(57) **CLAIM**

The ornamental design for a coaxial cable connector, shown in the shipping condition as shown and described.

DESCRIPTION

FIG. 1 is a perspective view of a new and ornamental design for a coaxial cable connector in its shipping condition. The internal details thereof are illustrated in the phantom are for environmental purposes only.

FIG. 2 is a side elevational view of the coaxial cable connector of FIG. 1; and,

FIGS. 3 and 4 are front and end views respectively of coaxial cable connector of FIG. 1, with the internal details being illustrated in phantom for environmental purposes only.
